UNITED STATES PATENT OFFICE.

CHARLES H. SPECKMAN, OF PHILADELPHIA, PENNSYLVANIA.

RADIATOR CONNECTION.

1,106,981.

Specification of Letters Patent. Patented Aug. 11, 1914.

Application filed June 18, 1910. Serial No. 567,724.

To all whom it may concern:

Be it known that I, CHARLES H. SPECKMAN, a citizen of the United States, residing in Philadelphia, Pennsylvania, have invented certain Improvements in Radiator Connections, of which the following is a specification.

My invention relates to valve connections for radiators of hot water heating systems and particularly to that type of valve connection which serves to separate the inflowing volume of hot water from the outflowing volume of cooler water, the object of my invention being to provide a valve connection of this type which will permit of a compact disposal of the devices connecting the same with the main or mains, and will provide for the cutting out of the radiator from the circulating system while still permitting a slow circulation of the water through the connections between the radiator and the supply pipe or main.

In the accompanying drawing Figure 1 is a longitudinal vertical sectional view of part of a radiator with valve connection in accordance with my invention, the valve being adjusted to position for directing the hot water to the radiator and discharging the cooler water therefrom; Fig. 2 is a similar view showing the valve adjusted to position for cutting out the radiator from the system but permitting a slow flow of the water through the valve connection, and Fig. 3 is a longitudinal sectional view illustrating a special feature of construction of one of the parts of the connection.

In the drawing, 1 represents the first section of a radiator. Screwed into or otherwise secured to the lower portion of said radiator section is the casing 2 of the valve connection, which consists of a horizontal tube with two vertical branches 3 and 4, and an internal horizontal partition 5, the latter being located, by preference, closer to the bottom than to the top of the casing 2 and being upturned at its inner end, as illustrated at 6, while its forward end terminates flush with the bore of the outer vertical branch 4. To this bore is fitted the valve 7 which consists of a hollow cylinder closed at the top and open at the bottom but having at one side a port 9, and at the opposite side a port 10, the top of the cylinder having a vertical stem 11 which passes through a suitable stuffing box on the top

of the casing 2 and is provided with a handle whereby it may be conveniently turned.

The branches 3 and 4 of the valve connection are in line longitudinally with one another and with the longitudinal line of the radiator, so that said branches can be readily connected, by short pipes and elbows, with branches on the incoming and return mains, or with branches disposed one alongside of the other and projecting from the inner side of a single supply pipe or main such as is employed in one-pipe heating systems. The radiator can therefore be located close to the main or mains and the simplest form of pipe connections can be used between said main or mains and the valve connection of the radiator.

The branch 4 of the valve connection is the inlet or supply branch and in a one-pipe system its pipe connections communicate with the upper portion of the main for receiving the hot water therefrom, the branch 3 constituting the outlet or discharge connection and its pipe connections communicating with the lower portion of the main in which the cooler water circulates. When the valve 7 is adjusted to the position shown in Fig. 1 the passage below the partition 5 is cut off from communication with the branch 4, but the hot water can pass freely through the port 9 of the valve into the passage above the partition from which it is discharged into the first section of the radiator, the upturned inner end of the partition 5 tending to direct the supply of hot water upwardly into said radiator section. The water, cooled by its circulation through the sections of the radiator, accumulates in the lower portion of the same and passes out beneath the partition 5 to the discharge branch 3. By reversing the position of the valve 7, as indicated in Fig. 2, the passage above the partition 5 is cut off from communication with the branch 4 and the inflow of hot water to the radiator is thereby arrested, but the port 10 serves to open communication between the branch 4 and the passage below the partition 5, and thus permits flow of water in limited volume from the branch 4 to the branch 3, thereby providing for a slow circulation of the water from the main to and through the valve connection without any corresponding flow through the sections of the radiators.

Instead of turning up the inner end of 110

the partition 5, the latter may, if desired, be connected to the lower part of the casing 2 so as to form an inwardly projecting nozzle, as shown for instance at 5^a in Fig. 3, 5 and this nozzle may be threaded for the reception of one end of a pipe 5^b, of any appropriate length, to provide for the discharge of the cool water from any desired portion of the radiator, even from that end 10 of the same which is opposite to the inlet end.

I claim:

A valve connection for radiators of hot water heating systems, said valve connection comprising a horizontal chest with horizontal partition therein dividing it into upper and lower chambers, an inner vertical branch communicating with the lower chamber only and an outer vertical branch com-

municating with both the upper and lower 20 chambers, and a hollow plug valve fitted to said outer vertical branch and having oppositely disposed ports whereby, when the valve is adjusted in one position, said branch will be in communication with the upper 25 chamber but will be cut off from the lower chamber and, when the valve is in the opposite position, said branch will be cut off from the upper chamber and in communication with the lower chamber. 25

In testimony whereof, I have signed my name to this specification, in the presence of two subscribing witnesses.

CHARLES H. SPECKMAN.
